ROLLER SKATE

John H. Lee, Jr., Oak Park, and Robert Lee Willis,
Chicago, Ill., assignors to Metal Specialties
Manufacturing Co., a corporation of Illinois

Application July 12, 1937, Serial No. 153,262

3 Claims. (Cl. 280—11.28)

This invention relates to roller skates and deals particularly with the class of roller skates which have rocking or tilting structure for mounting the rollers.

An object of the invention is to provide an improved skate construction in which the rollers are so mounted as to allow a maximum of cushioning effect so that a minimum of shock and vibration is transmitted to the top plate of the skate. Another object is to provide such a cushioned skate which is also well balanced and sturdy and which yields a feeling of security to the wearer.

Another object is to provide a skate in which the parts are at all times held in resilient engagement so that rattles and noises, etc., are eliminated.

Still another object is to provide an improved adjustable frame construction which can be firmly anchored in a desired adjustment.

An embodiment of the invention is illustrated in the accompanying drawings in which

Figure 1 is a plan view of the improved skate; Fig. 2, a view in side elevation; Fig. 3, a sectional view in elevation, the section being taken as indicated at line 3 of Fig. 4; Fig. 4, a longitudinal sectional view; and Fig. 5, a detail sectional view showing a cross section of the cushion, the section being taken as indicated at line 5 of Fig. 4.

As shown in the illustrations, A and A' designate front and rear frame plates which are connected by frame channel A²; B, the truck supporting members attached to the frame plates; C, the roller carriers to which the front and rear rollers are attached; and D, cushion members held between members B and carriers C.

The frame plates A and A' may be of any suitable construction. Front plate A is equipped with the usual toe clamp 10 by which the skate is secured to the sole of a shoe. On the top of the plate may be placed the rubber covering 11 which may be secured to the plate by means of the edge piece 12 having its top portion extending over the edge of covering 11 and its bottom portion secured to the bottom of plate A as by spot welding. At the rearward portion of plate A is a square opening 13 which is adapted to receive a square portion of the bolt 14. If desired, the plate may contain a slight top depression 15 to accommodate the head of the bolt and so as to make the top surface of the bolt flush with the top surface of the plate.

Frame plate A' preferably has the rear upturned flange 16 to which may be attached the heel piece 17. Covering 11^a may be placed over

plate A' and may be secured by edge pieces 12^a in a manner similar to that described in connection with plate A. Rear plate A' also has a bolt 14^a extending through square opening 13^a and having its head disposed in a slight depression 15^a.

The truck members B which are attached to plates A and A' have the upwardly extending side flanges 18 which at their upper edges are secured to the underside of the frame plates. The bottom or transverse portion 19 of each of the supporting members B is inclined with the horizontal. At the ends of this portion are the downwardly directed flanges 20 each of which is equipped with slots 21 extending longitudinally 15 of the flanges at their transverse centers. The bottom portion 19 with the flanges 20 form a type of yoke into which the cushion D is received.

The roller carriers C comprise a metal piece which is formed about an axle and provides a base 22 on which the cushion D is supported. At each of their ends carriers C are provided with the flanges 23 which extend upwardly between flanges 20 of members B. Each of flanges 23 is provided with slots 24 aligned with the slots 21. 25 The front roller carrier C is secured to the front axle 25 to which the front rollers 26 are mounted, and the rear carrier C is secured to the rear axle 25^a to which the rear rollers 26^a are mounted.

The cushion D is formed of a suitable resilient 30 material, preferably rubber, and is in the form of a rectangular block having a larger base than top. This cushion is placed between the supporting member B and the carrier C. If desired, a cap 27 may be placed over the top of this cushion 35 to keep the top edges from spreading. As shown more clearly in Fig. 5, this cushion is provided with an opening 28 extending longitudinally through it. Preferably opening 28 is extended vertically in the form of a slot so as to create 40 side wall portions 29 and 29^a of the cushion. It is important, however, that the opening 28 not extend to the top or bottom edges of the cushion for reasons which will appear more clearly hereinafter.

To secure the parts in place a pin 30 is extended through the slots of flanges 20 and 23 and through the opening 28 of the cushion. To insert the pin 30 in assembling the parts, it is necessary to flex the cushion D in two respects. In the first place, the top surface of the cushion must be pressed downwardly slightly to bring the slots of flanges 20 sufficiently into register to allow the pin to extend through each of the slots, and the walls 29 and 29^a of the cushion flex to allow this 55

movement. Secondly, the portion of the cushion immediately below pin 30 must be pressed downwardly to allow the pin to extend within the slots 24 and over this portion. The pin 30 may be held 5 in place by its head 30^a at one end and at its other end may be deformed to prevent its removal.

The frame plates A and A' are adjustably secured together by the channel piece A² which 10 has its transverse portion 41 provided with longitudinal slots 42 and 42^a. The front end of channel 40 extends under frame plate A and has the bolt 14 received within slot 42, and the rear end extends under plate A² and has the bolt 14^a received 15 within slot 42^a. The side flanges 43 of channel 40 engage the inside surfaces of the supporting members B, and as shown in Fig. 4, the inwardly struck portions 44 of the supporting members may engage flanges 43 to help maintain 20 the channel piece in position.

About each of bolts 14 and 14^a are the washers 45 which are rectangular in form and which have their side edges extending to the flanges 43. By 25 turning down the nuts 46 on bolts 14 and 14^a the washers 45 are drawn tightly against the channel 40 to secure this piece firmly with the plate. The use of the rectangular washers 45 is important first because the washer cannot turn within the channel and so allow the attachment to work 30 loose, and also because it engages the whole area of the transverse portion 41 for the length of the washer to effect a pressure over a greater area.

In this improved construction, the pin 30 is resiliently held at both of its ends, and it is engaged 35 only by the cushion D and by the sides of slots in flanges 20 and 23. Before the skate is loaded the pin 30 will be tightly held between the lower ends of slots 21 and the upper ends of slots 24. When the skate becomes heavily loaded 40 the walls 29 and 29^a of the cushion will flex allowing the member B to move slightly downward, the pin 30 moving within slots 21. It will be noted that even though disengaged from the ends of slots 21, the pin will not be loose or permitted 45 to rattle as the cushion portion immediately below the pin will resiliently hold it in engagement with the ends of slots 24.

When the skate passes over an uneven surface, the axles will tend to tilt, and in such case the 50 roller carriers C will turn pivotally about the pin 30 as an axis, the cushion D being flexed on one of its walls and relieved on the other. By having both front and rear of flanges 20 and 23 slotted, it is seen that there is no necessity of a 55 pivoting movement about one end of the pin such as is common in other constructions of this general type. Here the front and rear portions of cushion walls 29 and 29^a are equally flexed, and the movement about pin 30 is always free and 60 without binding.

The foregoing detailed description has been given for clearness of understanding only, and no unnecessary limitations should be understood 65 therefrom, but the appended claims should be

construed as broadly as permissible, in view of the prior art.

I claim:

1. In a roller skate, a frame plate, a truck member carried thereby, said member being provided with downwardly turned flanges each of which contains a slot, a roller carrier having upwardly turned flanges each of which contains a slot, a resilient cushion extending between said member and said carrier and having a vertically elongated opening extending longitudinally through the middle of said cushion, and a pin extending through the slots in said flanges and said opening in said cushion to secure the parts together, said opening in said cushion permitting vertical movement of said pin within said cushion and relative thereto, said pin being engaged only by the slots of said flanges and by said resilient cushion. 10 15

2. In a roller skate, a frame plate, a truck member carried thereby, said member being provided with downwardly turned flanges each of which contains a slot, a roller carrier having upwardly turned flanges each of which contains a slot, a resilient cushion extending between said member and said roller, said cushion having a vertically elongated opening extending longitudinally through the middle thereof, and a pin extending through the slots in said flanges and through the lower portion of said opening in the cushion to secure the parts together, said opening in the cushion providing flexing walls on each side of said pin and permitting vertical movement of said pin within said cushion and relative thereto, the bottom side of said cushion opening being in engagement with said pin whereby said pin is normally positioned in the lower portion of said cushion and said cushion being adapted to resiliently hold said pin against the upper ends of the slots in the flanges of said roller carrier. 20 25 30

3. In a roller skate, a frame plate, a truck member carried thereby, said member being provided with downwardly turned flanges each of which contains a slot, a roller carrier having upwardly turned flanges each of which contains a slot, a resilient cushion extending between said member and said roller, the base of said cushion adjacent said roller carrier being broader than the upper portion adjacent said member, said cushion having a vertically elongated opening extending longitudinally through the middle thereof, and a pin extending through the slots in said flanges and through the lower portion of said opening in the cushion to secure the parts together, said opening in the cushion providing flexing walls extending above the pin on each side thereof and permitting vertical movement of said pin within said cushion and relative thereto, the bottom side of said cushion opening being in engagement with said pin whereby said pin is normally positioned in the lower portion of said cushion and said cushion being adapted to 40 45 50 55

resiliently hold said pin against the upper ends of the slots in the flanges of said roller carrier. 60 65
